UNITED STATES PATENT OFFICE.

MICHAEL F. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST-PULLING MACHINE.

1,361,822.

Specification of Letters Patent. Patented Dec. 14, 1920.

Application filed May 19, 1915. Serial No. 29,204.

To all whom it may concern:

Be it known that I, MICHAEL FRANK BROGAN, a citizen of the United States, residing at Lawrence, in the county of Essex and 5 State of Massachusetts, have invented certain Improvements in Last-Pulling Machines, of which the following description, in connection with the accompanying drawings, is a specification, like reference characters on the drawings indicating like parts 10 in the several figures.

This invention relates to machines for separating shoes and lasts, such machines being commonly known in the trade as last 15 pulling machines, and it is the general object of this invention to provide an improved machine of this character.

In the process of manufacturing boots and shoes after the shoes have been lasted 20 and, when welt shoes are being manufactured, after the out soles and heels have been attached and the shoes have been substantially finished, it is necessary to separate the shoes from the lasts over which they have 25 been shaped. In the lasting operation the upper is drawn very tightly over the last and secured in the closest possible conformity to the last so that the operation of separating a shoe and last necessarily subjects 30 various parts of the shoe to considerable strain. For this reason, it is of great importance to the success of a last pulling machine that it be constructed and arranged to effect the last pulling operation with a 35 minimum straining of the shoe in order to prevent injuriously stretching, tearing, distorting or otherwise damaging the shoes so operated upon.

So far as I am aware, the first successful 40 last pulling machine to be devised is disclosed in United States Letters Patent No. 1,288,436, granted December 17, 1918 upon application of Benjamin F. Mayo, a modified form being shown in United States 45 Letters Patent No. 1,203,571, granted November 7, 1916, upon application of John M. Benjamin. The successful operation of the Mayo machine is due largely to the adequate way in which provision is made for 50 effecting separation of a shoe and last by relative movement of the shoe and last along lines of least resistance, and also to the construction of the parts of the machine for accommodation to different conditions, in-

cluding variety in the shapes of lasts and 55 shoes and in the different relative positions thereof during the operation of separating the shoe and last.

One object of the present invention is to 60 improve last pulling machines of the type disclosed in the above mentioned application by reducing still further the strains to which the shoe is subjected in the last pulling operation, and to improve the machine 65 in other respects. Accordingly, for the purposes of illustration and description, the present invention will be herein shown and described as embodied in a last pulling machine of the Mayo type. It must be comprehended, however, that the invention may 70 have other uses, including its applications and adaptation to last pulling machines of different types.

In accordance with the foregoing objects, 75 one feature of the machine herein described and shown consists in means for imparting an additional and different relative movement to the shoe and last holding means during the period of separating movement and in a direction to facilitate the separation of 80 the shoe and last. Preferably, this means is operated by power, as by a cam and operating connection from the same cam shaft through which the main relative separating movement is effected, and is actuated in timed relation to the first separating movement. As herein shown, one of 85 said holding means is first moved in a direction to separate the shoe and last and at a point in this separating movement, the other holding means is moved in the direction of relative separating movement. Preferably, and as shown, this additional 90 movement is effected at or about the point in the first separating movement when the last and shoe have been separated so that the last clears the counter of the shoe and is lengthwise of the shoe similarly to the first separating movement but in the opposite lengthwise direction. The second separating movement is instrumental in greatly 95 reducing the pulling strains upon the shoe particularly in the region of the throat of the vamp and adjacent parts of the upper which are especially affected by the relative passage of the extreme wide part of the last and the narrow opening at the 100 throat of the vamp.

Another feature of the invention consists in the provision of holding means for effecting a normal tipping of the shoe about its transverse axis and with the shoe forepart 5 free to rise, thereby facilitating the separation of the shoe and last and diminishing the strains to which the forepart and vamp throat are subjected in the separation of the shoe and last.

10 A further feature of the invention consists in the provision of means for engaging and folding the top of a shoe upper back toward the heel to facilitate the separation of the last and shoe by providing clearance 15 between the last and the upper. This feature, in the illustrated machine, consists of upper gripping means automatically positioned to engage and fold the top of the upper back toward the heel and subsequently to release the upper so that the shoe 20 is free when separation has been effected.

A further feature of the invention resides in the provision of means for loosening the shoe on its last to facilitate the separation of the shoe and last. As shown 25 herein, means are provided which are operative during separating movement and while the last is within the counter to spread or stretch the counter and thereby to facilitate the removal of the last heel from within 30 the counter. It will be understood that such stretching or spreading action will not be sufficient to injuriously affect the shoe and yet will be sufficient to lessen the strain 35 upon the forepart and vamp as well as upon the counter. In the illustrative machine I utilize the upper folding means to pull or stretch the upper in a manner tending to stretch or spread the upper part of the 40 counter.

Another feature of the invention consists in the provision of means for supporting the shank portion of the shoe against downward or rearward movement, which means 45 is adapted to be incorporated readily in a machine of the type disclosed herein. In accordance with this object of the invention, a feature of the machine illustrated herein consists in novel gripping means for 50 the shank portion of a shoe of a shape to grip the shank portion of the upper so as to prevent heelward movement of the shoe, said gripping means being so shaped as to oppose downward movement of the fore- 55 part of a shoe while permitting upward movement thereof.

Another feature of the invention, as embodied in the illustrated machine consists in the provision of a back member for the 60 heel portion of the shoe upper arranged to conform to the contour of said heel portion and to oppose rearward and downward movement thereof.

These and other features of the invention, 65 including certain novel means embodied in

the construction and arrangement of the illustrated shoe engaging devices, as well as other features will be apparent from the following detailed description read in connection with the accompanying drawings. 70

In the drawings,

Figure 1 is a view in side elevation of an illustrative machine embodying the present inventions, part of the machine frame being broken away to show inclosed mechanism; 75

Fig. 2 is a top plan view of the machine shown in Fig. 1;

Fig. 3 is a perspective view showing the shoe engaging and upper turning mechanisms; 80

Fig. 4 is a transverse, vertical, sectional view on the line 4—4 of Fig. 2;

Fig. 5 is a longitudinal, vertical, sectional view on the line 5—5 of Fig. 2; 85

Fig. 6 is an enlarged detail view showing in full lines the upper turning devices in operative engaging position relative to a shoe upper, the clamping position of the parts being shown in dotted lines; 90

Fig. 7 is a similar diagrammatic view showing the turning device in the position it occupies when operated to turn the upper backwardly toward the heel, the clamp releasing position of the parts being shown 95 in dotted lines;

Fig. 8 is a fragmentary, sectional view of the last jack illustrating an improved form of last pin and holder;

Fig. 9 illustrates a modified form of shank 100 gripping means.

The machine illustrated in the drawings comprises an upright column, having in its upper part a bearing sleeve 2, (Figs. 1 and 2) for a power driven shaft 4. The shaft 105 4 of the carriage carries a loose pulley 6 intended to be connected to a source of power, this pulley having one face formed as a clutch surface arranged to be engaged by a cone clutch member 8 splined on the 110 driven shaft 4. When permitted, the clutch member 8 is moved toward the right (Fig. 1) to engage the pulley and drive the shaft by a compression spring 10, mounted within the hub of the clutch member and 115 held between said clutch member and a suitable abutment, such as a portion of the shaft bearing 2. This spring is permitted to move the clutch member 8 to engage the pulley by a controlled floating lever 12 having a forked upper arm (Figs. 1 and 2) journaled at 14 on the movable clutch member 8 and controlled and operated at its lower end by a toggle 16—18. (Fig. 1) one end of which is pivoted to the floating lever, 125 the other end being pivotally mounted on the machine frame. A rod 20 is pivoted to the toggle at its central joint and depends therefrom and is itself pivotally connected to a treadle 22 pivotally mounted in the 130

machine frame. A spring 24 connects the treadle and machine frame and normally tends to pull the rod 20 downwardly to bring the toggle links into substantially alined position. In this position a dead center lock is afforded so that the lower end of the floating lever 12 is held fixed when the toggles are in alined or locking position. A stop pin 26 is preferably employed to prevent downward movement of the toggles beyond safe locking position and a turn buckle 28 provides for adjustment of the rod 20. When the treadle 22 is operated the toggle lock will be broken and the compression spring 10 will be permitted to move the clutch member 8 into engagement with the pulley, so that the shaft 4 is rotated.

To provide for automatically disengaging the clutch and stopping the driven shaft, the upper end of the floating lever 12 is pivotally connected at 30 to one end of a link 32 arranged to move to and fro and guided between fixed ears 34 upstanding from the bearing 2 in which the shaft 4 turns. The other end of the link 32 is forked to embrace the hub of a cam disk 36, fixed on the counter shaft 38. This counter shaft carries a fixed worm gear 40 meshing with a worm 42 fixed on the driven shaft 4, the construction of the machine being such that the counter shaft 38 makes one half of a revolution for each complete cycle of the machine. The end of the link 32 is guided upon the hub of the cam 36 so as to allow sliding movement of the link forwardly and backwardly parallel to the shaft 4. On one of its side faces within the plane of the cam, the link 32 has a projection 44, the outer edge face of which projection is curved and is eccentric to the axis of the counter shaft 38 carrying the cam 36. The action of the compression spring against the clutch normally tends to move the floating lever 12 and the connected link 32 so that this projection 44 is located to be engaged by one or the other of rolls 46, 48 carried on one side of the cam 36, such engagement forcing the link 32 toward the left (Fig. 1) and against the action of compression spring 10, thereby moving the floating lever in the direction to pull the clutch member 8 out of engagement with the pulley. The resistance offered to the roller 46 or 48 by the spring action against the projection is sufficient to brake and stop rotation of the counter shaft 38 substantially coincidently with unclutching action. It is necessary that the operator release the treadle as soon as the toggle has been broken and the clutch thrown, so that the spring 24 may raise the treadle and pull down the rod 20, again moving the links 16, 18 to alined locking position and fixing the lower end of lever 12 as its fulcrum during the automatic unclutching movement. In the position of the rest of the

parts, the cam carried roller acting against link projection 44 holds the upper end of the lever 12 stationary so that this end becomes the fulcrum of the lever 12 when the clutch is thrown in. This starting and stopping mechanism, specifically, forms no part of the present invention, but is shown as illustrating a desirable form of clutch mechanism for starting and stopping the machine with the parts in predetermined position.

For holding a shoe during the last pulling operation, the machine herein illustrated is provided with shoe engaging and holding means comprising members for engaging the sides and back of a shoe and with other means engaging and supporting the shoe in the region of the shank. In addition, an adjustable heel gage is employed.

To clamp the rear portion of the shoe, the illustrative machine is provided with counter and heel gripping means arranged to engage the sides and back of the shoe counter and, in one form, comprising curved plates 50, 52 having rearwardly offset ends pivotally connected so that the clamp is formed as a sectional hinged member arranged to engage the rear part of the counter at opposite sides of the longitudinal axis of the shoe. These plates are provided with ledges at their lower edges and have secured thereto by suitable means a block providing a gripping face of rubber or other suitable material which will not mar the material of the shoe. At the rear portion of the hinged clamp this material is not secured to the plates so that it forms a flexible conforming band adaptable to a large variety of sizes and shapes of counters. This facing is longitudinally concaved to the longitudinal contour of a shoe counter and is also vertically concaved to conform substantially to the vertical contour of the counter and to hold the shoe against downward movement at this point by reason of this concavity. Above the plates 50, 52 and at opposite sides are positioned channeled holders 54, 56 in which are mounted blocks of rubber or other suitable material concaved longitudinally and vertically to conform to the longitudinal and vertical contour of a heel. These gripper holders or plates are pivotally mounted and arranged to be moved to and from shoe engaging position. Except for differences due to opposed positions, the heel grippers are alike for both sides of the shoe. The counter plates 50, 52 and the heel block holders 54-56 are pivotally carried or swiveled on the inner ends of stems 60, each forming one of two telescoping sections 60, 64, between which suitable relief springs are mounted in each instance. Means for varying the tension of the springs are provided in the form of suitably threaded abutment nuts. 130

To provide for movement of these shoe clamping means into operative engagement with a shoe, the stems are carried by frames 64 which include the outer of the telescoping sections and which are movable endwise toward and from a shoe in guides in a gripper head 62. This gripper head 62 has outward extensions serving to guide opposed stems 66 carrying at their forward ends channel plates 68 in which are mounted shank gripping blocks 70 adjustable longitudinally of their plates 68, these blocks having a facing of rubber or other suitable material concaved to conform to the shank portion of the shoe upper, this concavity providing a shoulder or wedge face at the rear of the block to engage the enlarged shank portion of the shoe upper to prevent rearward movement of the upper when once clamped thereby. These gripping blocks engage the upper under yielding spring tension, and are guided for movement toward and from the shoe by means of slots formed in the stems and guide rolls carried by the head. The arrangement is such, that there may be adjustment of the stems and grippers to correspond with adjustment of the counter and heel grippers to adjust the shoe about its transverse axis. The heel grippers 54, 56 are normally swung on their pivots by light springs 58 so that they will be normally held open to permit the insertion of a shoe heel, the engagement of the heel with the inner part of the grippers moving them into correct clamping engagement. It frequently happens that unless the heel grippers are swung outwardly, as described, the heel will engage the grippers in the side adjacent the gripping face which will tend to block the entrance of the heel between the gripping faces, as will be evident. The use of springs to swing the grippers outwardly will prevent such a blocking or jamming action.

The frames 64, carrying the counter, heel and shank grippers, are operated to move to and from the shoe by connections from the counter shaft. The cam disk 36 has in its periphery two diametrically opposed and relatively short low parts or depressions, one of which is shown at 72, in Fig. 1. A bell crank 74 fulcrumed at 76 on the frame carries on its lower arm a roll 78 (Fig. 1) which engages the periphery of the cam disk 36 and moves its upper end to and fro as the cam rotates. The upper end of the bell crank 74 engages and intermittently thrusts toward the left (Fig. 1) and against the pull of return springs 80 a plunger 82 carrying at its end a cross head 84 (Figs. 2 and 3) connected by links 86 to the rear ends of bell cranks 88. These bell cranks are fulcrumed in the gripper head 62 of the machine and have their front arms linked by adjustable bars 90 to the sliding frames 64 carry-

ing the grippers. The starting position of the parts is shown in Fig. 1, from which it will be seen that the roller 78 of the bell crank normally rests in a low part or depression of the cam when the machine is at rest. When the clutch is thrown and the cam disk 70 is rotated, the roll 78 will ride up upon the high part of the cam and will move the upper end of the bell crank forwardly engaging the plunger 82 and, through the links and bell crank connections described, moving the frames 64 to bring their gripping blocks into engagement with their respective parts of a shoe which has been previously inserted between the grippers and is held supported therebetween on a suitable jack hereinafter described. The grippers will conform substantially to the contour of the shoe by reason of their pivots and relief springs and will be held firmly against the shoe so long as the roller 78 rides upon the high part of the cam 36. These gripping members are pivotally and yieldingly pressed against the shoe by reason of the relief springs operating against their stems. They will, therefore, conform to a wide range of shoes and their relief springs will prevent injurious clamping pressure.

The head 62 in which the frames 64 are guided and by which they are carried, is provided with downward extensions 92 positioned below the plates or blocks 50, 52 and provided with two or more set screws 94 or other similar means for adjustably supporting the grippers at an angle to the horizontal, so that these grippers may so support the shoe as to effect a normal tipping of the shoe about its transverse axis. The plates or blocks carrying the heel grippers and the counter grippers being superposed, adjustment of the counter grippers by means of the set screws 94 will likewise adjust the heel grippers at a corresponding inclination. The shank grippers are capable of turning movement, to conform to the inclination of the counter and heel grippers as before stated.

This normal tipping of the shoe about its transverse axis has been found to be very advantageous in that it positions a shoe at an angle wherein the strain against the parts 115 during separation is materially lessened. Furthermore, the grippers being spring-pressed and pivoted will yield sufficiently to allow upward tilting of the forepart of the shoe during the last pulling operation.

In order to engage the top lift of the heel so as to properly gage the position of the shoe relative to the heel and counter grippers, an arm 96 extends outwardly from the gripping head and is formed with a bore therein and with a set screw to support adjustably a horizontal bar 98 extending outwardly therefrom and formed with a

vertical bore and set screws. Depending from the bar 98 and adjustably carried thereby is a gage bar 100, to the lower end of which is journaled a heel gage 102 pivotally carried by the bar 100 and adjustable in the direction of the length of the shoe by means of a clamping screw carried by the bar operating against an upstanding ear on the gage plate. The inclination of this gage plate can be adjusted to conform to the inclination of the heel and counter grippers, (Figs. 4 and 5).

If desired, the shank gripping block with its rubber pad may be dispensed with and the welt crease of the shank may be engaged at opposite sides by suitable means. One form that such means may take is shown in Fig. 9 of the drawings, in which 104 represents the slotted spring-pressed stem and 20 106 the gripper head through which it is guided. The forward end of the stem is formed as a tubular portion 108 having its outer face grooved to receive a vertically sliding bar 110 having a thin foot 112 designed to enter into the welt crease. The upper end of this bar is offset and is adapted to receive an adjusting screw whose lower end enters into the tubular portion of the stem and is yieldingly supported by a spring 30 114 held therein. At its opposite end, the bar is provided with a finger 112 arranged to engage in the welt crease of the shank. A pair of these welt crease engaging members will be used, one on each side of the 35 shoe. It will be evident that the spring described provides means for yieldingly supporting the shoe at this point.

For engaging and holding a last and withdrawing it from its shoe while the shoe is 40 held by the clamping devices heretofore described, the illustrated machine is provided with a last support and holder comprising a spindle 116 (Fig. 3) carried on the front end of a swinging carrier 118 pivotally connected at its rear end at 120 to the upper end 45 of one arm of a bell crank. This bell crank is fulcrumed at 122 on the upper end of a plunger 124, having an offset at its upper end, with which the other arm of the bell crank engages when the last spindle is 50 in its lowered position. The spindle 116 is provided with a vertical socket therein, counterbored adjacent its base to receive a latch pin 126 normally spring-pressed into 55 the socket and having an operating finger piece 128 extending outwardly through a slot formed in the swinging carrier 118. The last pin 130 is formed adjacent its lower end with an annular groove 132 therein into 60 which the latch 126 enters, serving to detachably retain the latch pin in the last spindle. This pin and groove connection in combination with the pivotal mounting of the carrier provides a mounting for the 65 last pin enabling the pin to turn freely with the last as it turns in being removed from the shoe so as to give as nearly as possible a straight line pull on the last. Intermediate its ends, the last pin is formed with a shoulder designed to rest upon the 70 upper end of the spindle to properly position the pin. The upper end of the pin is preferably shouldered down adjacent its end to form an annular shoulder 134 which will afford a biting grip against the thimble 75 of the last hole.

The lower end of the plunger 124 is pivotally secured to one end of a cross bar 136 the opposite end of which is fulcrumed on the machine frame at 138. An operating 80 bar 140 is pivoted at its lower end to a cross bar 136 at a point intermediate its ends. The upper end of the bar 140 is forked to embrace and be guided by the hub of the cam 36. Below its fork it carries a 85 roller 142 (Fig. 1) lying in the plane of oppositely disposed wiper cams 144 carried upon the face of the cam 36 opposite the rollers 46, 48. These wiper cams will engage the roller 142 at a point in the operation of the machine subsequent to the operation of the bell crank 74 to move the grippers into shoe gripping position, and will move the bar 140 downwardly against the action of a counter weight 146 acting 90 95 against one end of the bar and normally tending to move it upwardly. This downward movement of the bar 140 will take place after the shoe has been gripped and will act against the plunger 124 to move 100 the latter downwardly. This downward movement of the plunger will, through the bell crank and its connected carrier 118, first tilt the spindle and last pin lengthwise heelward of the last to clamp the last pin in 105 the last pin hole and securely grip the last, and will then exert a downward pull on the last in a direction substantially perpendicular to the plane of the shoe bottom. This movement takes place against the resistance 110 of the clamped shoe. The relief springs co-operating with the shoe gripping devices make the initial resistance to pull a yielding one so that the start of the last pulling is effected without any sudden strain being 115 imparted to the upper. Downward movement of the plunger pulls the last downwardly in the vertical plane referred to and lengthwise of the shoe and last until the last is completely removed from the shoe. By 120 reason of the pivotal connections of the carrier and bell crank, the plunger at all times during its descent exerts upon the last spindle a distinct and increasing backward pull, so that during its generally downward last 125 extracting movement, the last spindle is caused to exert upon the last a constant and progressively increasing pull in a heelward direction. The result is that, as the last is moved downwardly, it is also moved length- 130

wise relatively to the shoe as much as is permitted by the relative positions of the last and shoe. This lengthwise movement during the initial stages of last pulling, is very slight and until the last has been moved downwardly far enough to clear the counter portion on the shoe, only very slight lengthwise movement is permitted, this portion of the movement being substantially perpendicular to the plane of the shoe bottom. As soon as the heel of the last clears the counter of the shoe, the last is permitted to have a very decided lengthwise movement. During the last pulling operation the gripping devices prevent downward movement on the part of the shoe but as the grippers are yieldingly pressed into engagement with the shoe, the downward and rearward pull on the last will be effective to swing the forepart of the shoe upwardly to some extent and to that angle which is effective to lessen the resistance to pull and facilitate extraction of the last.

Even with the heretofore described provisions for lessening strain on the shoe and facilitating the separation of shoe and last, the shoe is still subjected to severe strain, particularly at and about the throat of the vamp, which may injure shoes in certain cases and under certain conditions. I have therefore provided means for additionally relieving the strain of separation and for facilitating this operation. In the illustrative machine this is accomplished by moving the shoe with its grippers relative to the last and in the direction of length of the shoe while the last is being moved relative to the shoe.

The gripper head 62 which extends out from the machine and carries the various gripper members, has a flanged base 154 supported and guided in ways 156 in the machine frame (Figs. 1 and 2), and slideable in the direction of length of the shoe and last. At the under side of the head 62 a lug 158 (Fig. 5) projects downwardly. A cam lever journaled on the machine frame at 160 has its upper end pivotally connected with the lug 158 by a link 162. The lower end of this lever is enlarged and formed with a cam slot 164 therein (Fig. 1). The upper forked end of the bar 140 is provided with a lateral offset 166 carrying a roller 168 riding in the cam slot 164. This cam slot and roller are figured to operate against the cam lever to move link 162 and the gripper head forwardly at that period in the downward last pulling movement of bar 140 when the last heel has substantially cleared the counter. This forward movement of the gripper head will move the shoe and grippers bodily forward in the direction of length of the shoe at the time that the last is being moved lengthwise in the opposite direction and at that time when the wide

part of the last is passing the narrower part of the shoe upper and is therefore subjecting it to considerable strain. This strain is materially lessened by the bodily movement of the gripped shoe in the opposite direction. This movement will prevent binding of the last on the shoe and will increase the speed of the last pulling operation. When the wiper cam 144 passes beyond the roller 142 and permits the counter weight and its assister spring, hereinafter described, to raise the bar 140, the upward movement of the roller 168 will act against the cam lever to retract the link 162 and gripper head 62. It will be evident that when the gripper head is moved forward bodily, the plunger 82 will be moved rearwardly relatively thereto by springs 80 to lessen the gripping pressure on the shoe unless it is held in its fully forward position. In the illustrative machine I have formed a notch 170 in the underside of the plunger (Fig. 1) and have mounted in said gripping head a spring latch 172 designed to enter in the notch 170 when the plunger is moved to 90 fully forward position. A link 174 is pivotally attached at its upper end to this latch and has its lower depending end formed as a loop in which the roller 168 also extends. When the bar 140 reaches the limit of its 95 downward last pulling movement it engages the bottom of this loop and pulls the link downwardly retracting the latch 172 and permitting the return spring 80 to retract the plunger.

It frequently happens that when "high" shoes are being treated the last sticks because of the binding or blocking action of the top or high part of the "high" shoe quarter which, for the sake of brevity, I 105 will term the "upper". I have therefore provided means for turning back this upper toward the heel so as to afford clearance between the last and the shoe. I have also arranged this means to exert a stretching 110 or spreading pull on the upper part of the counter acting to stretch the counter and to facilitate the separation of the last from that portion of the shoe. In the illustrative machine, an upper turning head 176 115 is carried by the gripper head, being guided upon a standard 180 for vertical sliding movement. The head 176 has a depending arm bifurcated at its lower end to provide laterally extending arms 178 shaped to conform substantially to the outline of the rear of a shoe upper and arranged to inclose and guide the upper to the gripping elements supported by these arms. At their outer extremities these arms have bearings 182 extending in line with the arms and at an angle to the longitudinal median line of a shoe so as to conform substantially to the divergence of a shoe upper from the back stay forwardly. The jack spindle 116 and 130

carrier 118 extend between these arms and bearings so that when the last is mounted on the last pin of the jack and the latter is swung upwardly to position the shoe in coöperative relation to the counter, heel and shank grippers the rear portion of the sides of the upper will extend within the area inclosed by the arms 178 and will be in line with and in coöperative relation to the turning grippers. Except for differences due to opposed positions the construction of each turning gripper is the same. Each comprises a crank having an arm 184 extending through and journaled in a bearing 182 and retained therein by the sleeve 186 fixed to the end projecting beyond the bearing 182. It is desirable for reasons herein-after stated, to provide a "drag" or slight resistance to turning movement of the crank arm in the bearing and for this purpose friction springs 188 (Figs. 6 and 7) may be seated in the bearings 182 to act against the crank sleeves 186. The other arms 190 of the cranks carry the turning grippers, one rigidly secured thereto and the other mounted thereon for slight relative turning movement toward and from the upper positioned between the grippers. The fixed gripping and turning members comprise curved fingers 192 whose convex outer faces are adapted to engage the last spindle, when the head 176 is lifted, and be guided thereby outwardly toward the upper. The relatively movable grippers 194 are journaled on the arms 190 at one side of the fingers 192 and have their extremities formed as offset fingers 196 positioned opposite the gripping ends of the fingers 192. The relative turning movement of these fingers 194 on the arm 190 may be limited by a pin on the crank and a recess in the adjacent journal portion of the finger (Figs. 3, 6 and 7) or any other suitable means. The grippers 194 are also preferably bent outwardly (as best seen in Figs. 6 and 7) to afford, in conjunction with the concaved faces of fingers 192, ample space between the grippers to receive the shoe upper. The grippers 194 are journaled on the arm 190 between their ends, their free ends extending below the bearings 182 (Figs. 3, 6 and 7) at an angle to the vertical. The grippers have their opposite ends pivotally connected to the upper ends of operating rods 198 designed to first move the gripper 194 relative to the finger 192 to grip the upper and designed subsequently to move the grippers as a whole about the center formed by the axis of the crank arm 184. The limited relative movement of gripper 194 is permitted because of the "drag" or frictional resistance of the springs 188 to turning movement of the crank. At the end of this relative free movement of arm 194 to grip the upper, the continued movement of the rods 198 up-

wardly turns the grippers as a whole about the axis of crank arm 184 in opposition to the drag of the springs 188.

The operative gripping parts of the members 192, 194 are positioned beyond and eccentric to the axis of rotation to the gripper so that a pull is exerted upon the upper outwardly of the shoe, serving not merely to facilitate turning of the upper, including the back-stay, backwardly toward the heel, but exerting substantial outward pull against the upper portion of the shoe counter to effect a stretching of the counter to facilitate last removal. The grippers are positioned to engage the upper on opposite sides of and adjacent to the back stay so that the turning action under tension of the upper is effective to turn the back stay with the upper despite the comparative stiffness of the back stay.

The machine frame is provided with an offset 200 at a point below the turning head. This offset is provided with inclined elongated slots 202 therein through which the rods 198 extend, the elongation of these slots being in the direction of movement of the rods when the gripper head, including the turning head 176, is moved bodily forward. The lower ends of these rods are pivotally attached to a floating cross bar 204. Springs 206 coiled about the rods 198 between the under face of the offset 200 and abutment washers on the rods, act against these rods and normally tend to pull them downwardly to position the grippers and their associated parts as shown in Figs. 1 and 3. At a point between the ends of the cross bar a chain 207 is attached and extends upwardly and over a pulley 208 mounted at the underside of offset 200. The end of this chain is pivotally secured to the end of an arm 210 extending outwardly and rigidly from the cross-bar 136 of the last pulling mechanism.

The cross head 84 of the shoe-gripping mechanism is provided at opposite sides with trunnions, one of which is shown at 212 in Fig. 3. On the gripper head at opposite sides of the upper turning head 176, bell cranks 214 (Fig. 3) are journaled, these bell cranks having their lower arms provided with pins resting in the trunnions 212. The upper ends of these bell cranks are pivotally connected by adjustable depending links 216 with the upper turning head 176. These links provide for adjustment of the turning head vertically of its standard 180.

When the shoe-gripping cross-head 84 is moved forwardly to grip the shoe the trunnions 212 rock the bell cranks 214 and raise the gripping head 176 relative to the shoe supported by the counter, shank and heel gripping devices heretofore described. The arms 178 of the turning head will have pre-

viously confined the shoe upper between them and substantially in line with the turning grippers. As the head is thus moved upwardly on shoe gripping movement of the machine the pull on the rods 198 will swing the grippers slightly outward from the shoe to the position shown in full lines in Fig. 6 the curved finger engaging the last and guiding the top edge 10 of the shoe upper into the space between the grippers. This will be the position of the parts when the last pulling movement of the bar 140 begins to pull down the cross bar 136 and its extension arm 210. The chain 15 207 will be pulled upwardly moving the bar 204 and the rods 198 upwardly and compressing the springs 206. The first movement of the rods will move the gripping arms 194 inwardly toward the fixed grippers 192 firmly gripping the upper. Continued upward movement of the rods will turn the grippers as a whole about arms 184 as axes turning the upper backwardly toward the heel as heretofore described, and 25 stretching the upper part of the counter because of the outward pull on the upper. This turning and stretching action occurs at the commencement of the last pulling movement and before the last has cleared 30 the counter and therefore at the time when counter stretching is effective to assist in the pulling of the last from the counter. The upper is also sufficiently turned before the last clears the counter so that the upper 35 is out of the way and clearance is afforded without any delay. When the last clears the counter the gripper head is moved to carry bodily outward the shoe with its gripping and turning mechanism so as to move 40 the shoe relative to the last in the direction of length of the shoe reverse to that in which the last is being withdrawn, thereby loosening the forepart of the shoe on the forepart of the last and greatly facilitating 45 and expediting the separation of the shoe and last. The elongation of the slots 202 in which the upper turning rods are guided, provides for swinging movement of these rods during such forward movement. The 50 movement of the grippers during the final stage of last pulling movement is comparatively slight and the parts in their final upper turned position are substantially as represented in Fig. 7. When the wiper cam 144 clears roller 142 the compressed springs 206 operate to first move the finger 196 to release the upper and then turn the grippers as a whole about the axis of arm 184 and back to original position, the head 55 60 dropping as the shoe-gripper cross head 84 is returned and both the shoe-gripper and upper turning heads being moved rearwardly through counter weight 146, assisted by compressed springs 206, 65 acting to elevate the bar 140.

Owing to the use of lasts having instep blocks which must be pulled before the last may be pulled from the shoe, it is necessary to provide means for extracting these blocks. Accordingly, at one side of the 70 gripping head of the machine and adjacent the last spindle, an arm 148 is secured to and depends from the gripper head and has a pin 150 detachably secured in a socket formed in its end, said pin having one end 75 arranged to enter into the arm socket and having its other end formed with complementary spring arms 152, arranged to be inserted through the hole in the instep block to engage and release the plunger or latch, 80 the spring arms yielding and being pressed together during this action, and being pressed against the block with sufficient force to hold said block when the last is pulled away. Consequently a workman, before mounting the last upon the last pin 130 and swinging up the carrier 118 to present the shoe between the grippers, has only to move the last toward the arm 148 so as to insert the spring arms 152 into the hole 90 in the instep block and then pull the last away, the spring arms retaining and withdrawing the block. The last may then be spindled upon the carrier 118 and the latter moved up to position the shoe between the 95 grippers. This block extracting device forms the subject-matter of United States Letters Patent No 1,288,459, granted December 24, 1918, upon a divisional application.

100

It is to be understood that the expression "last pulling machine" and kindred expressions employed in the claims and elsewhere herein, are to be construed as limited in scope to a machine for pulling lasts from 105 shoes only when necessarily and plainly so restricted by the immediate context or by the prior art, such expressions being employed in a generic sense to designate the separation of a shoe and last, however accomplished.

110

What I claim, therefore, as new, and desire to secure by Letters Patent of the United States is:

1. A last pulling machine having, in combination, shoe holding means, last holding means, mechanism constructed and arranged relatively to move said holding means in a direction to separate the last and shoe, and means arranged to effect additional relative 115 separating movement of the shoe and last holding means during the period of separation in a different direction to facilitate separation of the last and shoe.

120

2. A last pulling machine having, in combination, shoe holding means, last holding means, mechanism constructed and arranged to effect relative movement of the shoe holding means and last holding means in a direction to separate the shoe and last, and 125 130

means arranged to effect additional and different relative movement of said holding means in timed relation to said first relative movement and in a direction to facilitate the 5 separation of the shoe and last.

3. A last pulling machine having, in combination, shoe holding means, last holding means, and power operated mechanism organized to effect relative movement of the 10 shoe and last holding means in a direction to separate the shoe and last and at a point during said first movement automatically to effect a second separating movement in a different direction to facilitate last and shoe 15 separation.

4. A last pulling machine having, in combination, shoe holding means, last holding means, mechanism for effecting relative movement of said shoe and last holding 20 means in a direction to separate the shoe and last, an operating shaft, and power transmitting connections from said shaft effective to impart additional relative separating movement to said shoe and last holding 25 means to facilitate the separation of the shoe and last.

5. A last pulling machine having, in combination, shoe holding means, last holding means, power operated mechanism organized to effect relative movement of said holding means in a direction to separate the shoe and last, and means operated in predetermined timed relation to the relative separating movement of said holding means 30 to impart additional relative separating movement to said holding means and thereby facilitate the operation of the machine.

6. A last pulling machine having, in combination, shoe holding means, last holding 40 means, mechanism organized relatively to move said shoe and last holding means in a direction, including movement in a direction lengthwise of the shoe and last, to separate a shoe and last, and means for effecting 45 additional lengthwise separating movement of said shoe and last holding means in a different direction during the period of the first movement to facilitate the longitudinal separation of the shoe and last.

7. A last pulling machine having, in combination, shoe holding means, last holding means, and power operated mechanism organized to effect movement of one of said holding means relatively to the other in a 50 direction to separate a shoe and last and operative in timed relation to said separating movement to effect movement of the other of said holding means relatively to the first holding means and in a direction to facilitate said separation.

8. A last pulling machine having, in combination, shoe holding means, last holding means, mechanism for moving one of said holding means relatively to the other in a

direction to separate a shoe and last, and 65 mechanism operative during said separating movement to move the other of said holding means in the direction of relative separating movement to facilitate separation.

9. A last pulling machine having, in combination, shoe holding means, last holding means, and mechanism organized to effect relative last and shoe separating movement of said last and shoe holding means first in a direction substantially perpendicular to 70 the plane of the shoe bottom and then lengthwise of the shoe and including means operative to effect simultaneous lengthwise movement of said shoe and last holding means in reverse directions to facilitate separation. 75

10. A last pulling machine having, in combination, shoe holding means, last holding means, and power operated mechanism, for effecting last and shoe separating movement of one of said holding means relatively to the other in a direction first substantially perpendicular to the plane of the shoe bottom and then lengthwise of the shoe and for imparting lengthwise movement to said 80 other holding means coincidently with and in a direction reversely to lengthwise movement of the first holding means. 85

11. A last pulling machine having, in combination, means for holding a shoe, means for holding a last, mechanism constructed and arranged to move one of said holding means relative to the other to separate the last and shoe, and means for moving said other holding means relative to the first 90 during the period of said separation to facilitate the separation. 100

12. A last pulling machine having, in combination, means for holding a shoe, means for holding a last, mechanism constructed and arranged to move one of said holding means relative to the other to separate the shoe and last, and means for moving said other holding means relative to the first in timed relation to and during said first mentioned movement to facilitate the separation. 105

13. A last pulling machine having, in combination, means for holding a shoe, means for holding a last, mechanism constructed and arranged to move one of said holding means relative to the other to separate the last and shoe, and means cooperating with said mechanism and operated thereby to move said other holding means relative to the first 115 during the pendency of said first mentioned relative movement.

14. A last pulling machine having, in combination, means for holding a shoe, means for holding a last, mechanism constructed and arranged to move said last holding 125 means in a direction to separate the last from the shoe, and means operative to move

said shoe holding means relative to said last holding means and in a direction to separate the shoe from the last.

15. A last pulling machine having, in combination, means for holding a shoe, means for holding a last, mechanism constructed and arranged to move said last holding means in a direction to separate the last from the shoe, and means operative during 10 such separating movement to move said shoe holding means relative to said last holding means and in a direction to separate the shoe from the last.

16. A last pulling machine having, in combination, means for holding a shoe, means for holding a last, mechanism constructed and arranged to move said last holding means in a direction to separate the last from the shoe, and means operative at a 20 point during such separating movement and subsequent to the initiation thereof to move said shoe holding means relative to said last holding means and in a direction to separate the shoe from the last.

25. 17. A last pulling machine having, in combination, means for holding a shoe, means for holding a last, mechanism constructed and arranged to move said last holding means in a direction to separate the last from the shoe, and means, operative approximately when the last has been moved to 30 clear the shoe counter to move said shoe holding means relative to said last holding means and in a direction to separate the shoe from the last.

40. 18. A last pulling machine having, in combination, means for holding a shoe, means for holding a last, mechanism constructed and arranged to effect relative movement of 45 said shoe holding means and said last holding means in a direction substantially perpendicular to the plane of the shoe bottom and then in a direction generally lengthwise of the shoe and last to separate said shoe and last, and means for effecting other and additional movement between said shoe and last during the period of separation to facilitate such separation.

50. 19. A last pulling machine having, in combination, means for holding a shoe, means for holding a last, mechanism constructed and arranged to effect relative movement of 55 said shoe holding means and said last holding means in a direction substantially perpendicular to the plane of the shoe bottom and then in a direction generally lengthwise of the shoe and last to separate said shoe and last, and means, operative when 60 said shoe and last have been separated to clear the shoe counter, for effecting other and additional movement between said shoe and last in a direction lengthwise of said shoe and last during the period of separation to facilitate such separation.

20. A last pulling machine having, in combination, means for holding a shoe, means for holding a last, mechanism constructed and arranged to effect relative movement of 70 said shoe holding means and said last holding means in a direction substantially perpendicular to the plane of the shoe bottom and then in a direction generally lengthwise of the shoe and last to effect separation of said shoe and last, and means, co-operating with said mechanism and operative when said shoe and last have been separated to clear the last heel and shoe counter, for effecting other and additional movement between 75 said shoe and last, in a direction lengthwise of the shoe during the period of separation to facilitate such separation.

21. A last pulling machine having, in combination, means for holding a shoe, means for holding a last, mechanism constructed and arranged to pull a last from within a 80 shoe by movement of said last holding means relatively to said shoe holding means in a direction substantially perpendicular to the plane of the shoe bottom and then in a direction generally lengthwise of the shoe and last, and means operative subsequently to the initiation of said last pulling movement, for moving the said shoe holding means to move said shoe relative to said last.

22. A last pulling machine having, in combination, means for holding a shoe, means for holding a last, mechanism constructed and arranged to move said last holding means relatively to said shoe holding means in a direction substantially perpendicular to the plane of the shoe bottom and then in a direction generally lengthwise of the shoe and last to separate said last from 100 said shoe, and means operative subsequently to the initiation of said separating movement, for moving said shoe holding means to move said shoe relative to said last and in a direction substantially lengthwise 105 of said shoe and last.

23. A last pulling machine having, in combination, means for holding a shoe, means for holding a last, mechanism constructed and arranged to move said last holding means relatively to said shoe holding means in a direction substantially perpendicular to the plane of the shoe bottom and then in a direction generally lengthwise 110 of the shoe and last to separate said last from said shoe, and means operative when said last has been moved to clear the shoe counter, for moving said shoe holding means to move said shoe relative to said last and in a direction substantially lengthwise of 115 said shoe and last.

24. A last pulling machine having, in combination, a head, gripping means carried thereby arranged to hold a shoe, means for holding a last, mechanism for moving 120

said last holding means relatively to said shoe and head in a direction substantially perpendicular to the plane of the shoe bottom and then in a direction generally lengthwise of the shoe and last to effect separation of said last from said shoe, and means operative to move said head and shoe relatively to said last to effect separation of said shoe from said last during the separation of said last from said shoe.

25. A last pulling machine having, in combination, a movable head, gripping means carried thereby arranged to be operated to grip and hold a shoe, means for holding a last, means for operating said gripping means to hold a shoe, mechanism for moving said last holding means relative to said shoe and head in a direction substantially perpendicular to the plane of the shoe bottom and then in a direction generally lengthwise of the shoe and last to separate said last from said shoe, and means operative to move said head and gripped shoe in a direction lengthwise of the shoe and last and relative to said last to separate said shoe from said last during the pendency of the first separating movement.

26. A last pulling machine having, in combination, a head, gripping means carried thereby arranged to hold a shoe, means for holding a last, mechanism for moving said last holding means relative to said shoe and head in a direction substantially perpendicular to the plane of the shoe bottom and then in a direction generally lengthwise of the shoe and last to effect separation of said last from said shoe, and other mechanism coöperating with said first mentioned mechanism and operated thereby when the last has been moved to clear the shoe counter to move said head and shoe relative to said last in a direction lengthwise of the shoe and last to effect separation of said shoe from said last.

27. A last pulling machine having, in combination, means for holding a shoe, means for holding its last, means for effecting relative movement between said shoe and last in a direction to effect separation of said shoe and its last, and means for folding the top of the upper back toward the heel to facilitate such relative separating movement.

28. A last pulling machine having, in combination, means for holding a shoe, means for holding a last, means for effecting relative movement between said shoe and last in a direction substantially perpendicular to the plane of the shoe bottom and then in a direction generally lengthwise of the shoe and last to effect separation of said shoe and last, and means operative during such separating movement to fold the top of the shoe upper back toward the heel to

afford clearance between the last and shoe upper.

29. A last pulling machine having, in combination, means for holding a shoe, means for holding a last, mechanism for effecting relative movement between said shoe and last in a direction substantially perpendicular to the plane of the shoe bottom and then in a direction generally lengthwise of the shoe and last to effect separation of said shoe and last, and means controlled by said mechanism and operative during separating movement to fold the top of the shoe upper back toward the heel to afford clearance between the last and shoe upper.

30. A last pulling machine having, in combination, means for holding a shoe, means for holding a last, means for effecting relative movement between said shoe and last in a direction to effect separation of said shoe and last and means operative during such separation to fold the top of the upper back toward the heel to afford clearance between the last and shoe upper, said means being subsequently operable to unfold the upper.

31. A last pulling machine having, in combination, means for holding a shoe, means for holding a last, mechanism for effecting relative movement between said shoe and last in a direction to effect separation of said shoe and last, and means coöperating with said mechanism and operative during such separation to fold the top of the upper back toward the heel to afford clearance between the last and shoe upper, said means being subsequently operable to unfold the upper.

32. A last pulling machine having, in combination, means for holding a shoe, means for holding a last, mechanism for effecting relative movement between said shoe and last in a direction substantially perpendicular to the plane of the shoe bottom and then in a direction generally lengthwise of the shoe and last to effect separation of said shoe and last, and means for folding the top of the upper back toward the heel prior to relative lengthwise movement between the last heel and shoe in a direction to engage the heel of the last with the shoe upper.

33. A last pulling machine having, in combination, means for holding a shoe, means for holding a last, mechanism for effecting relative movement between said shoe and last in a direction substantially perpendicular to the plane of the shoe bottom and then in a direction generally lengthwise of the shoe and last to effect separation of said shoe and last, and means for folding the top of the upper back toward the heel prior to relative lengthwise movement between the last heel and shoe in a direction to engage the heel of the last with the shoe upper, said

means coöperating with said separating mechanism and being automatically operated thereby.

34. A last pulling machine having, in combination, means for holding a shoe, means for holding a last, mechanism for effecting relative movement between said shoe and last to effect separation of said shoe and last, and means automatically engaging and 10 turning the shoe upper back toward the heel to facilitate shoe and last separation and subsequently operative to release said upper.

35. A last pulling machine having, in combination, means for holding a shoe, 15 means for holding a last, mechanism for effecting relative movement between said shoe and last in a direction to effect separation of said shoe and last, and means arranged to engage the shoe upper at opposite sides of 20 and adjacent the back stay and to turn said upper back toward the heel to afford clearance between the last heel and shoe upper.

36. A last pulling machine having, in combination, means for holding a shoe, 25 means for holding a last, mechanism for effecting relative movement between said shoe and last in a direction to effect separation of said shoe and last, and gripping means automatically operative to engage the shoe upper 30 at opposite sides of and adjacent the back stay and to turn said upper back toward the heel to afford clearance between the last heel and shoe upper.

37. A last pulling machine having, in combination, means for holding a shoe, 35 means for holding a last, mechanism for effecting relative movement between said shoe and last in a direction to effect separation of said shoe and last, and gripping means automatically operative to engage the shoe upper 40 at opposite sides of and adjacent the back stay and to turn said upper back toward the heel to afford clearance between the last heel and shoe upper, said means being subsequently and automatically operated to 45 release the upper.

38. A last pulling machine having, in combination, gripping means movable to engage and hold a shoe, means for holding a 50 last, mechanism operable to move said gripping means to engage and hold a shoe and subsequently operable to effect relative movement between said shoe and last in a direction to effect separation of said shoe 55 and last, and means coöperating with said mechanism to engage and turn the shoe upper back toward the heel to afford clearance between the last heel and shoe upper.

39. A last pulling machine having, in combination, gripping means movable to engage and hold a shoe, means for holding a last, mechanism operable to move said gripping means to engage and hold a shoe and subsequently operable to effect relative move- 60

ment between said shoe and last in a direction to effect separation of said shoe and last and means coöperating with said mechanism and operative to engage the top of the upper at opposite sides of and adjacent the back stay and to turn the upper back toward the heel to afford clearance between the last heel and shoe upper. 65

40. A last pulling machine having, in combination, gripping means operable to engage and hold a shoe, means for holding a last, mechanism operable to move said gripping means to engage and hold a shoe and subsequently operable to effect relative movement between said shoe and last in a direction to effect separation of said shoe and 70 last, and means coöperating with said mechanism and automatically operated thereby to engage the top of the shoe upper at opposite sides of and adjacent the back stay and to turn the shoe upper back toward the heel to afford clearance between the last heel and shoe upper. 75

41. A last pulling machine having, in combination, gripping means movable to engage and hold a shoe, means to hold a last, 80 mechanism operable to move said gripping means to engage and hold a shoe and subsequently operable to effect relative movement between said shoe and last in a direction to effect separation of said shoe and last, movable upper turning means coöperating with said mechanism and movable into operative upper turning relation upon shoe engaging movement of said shoe-gripping means, with means controlled by said mechanism subsequently to operate said turning means to turn the top of the shoe upper back toward the heel to afford clearance between the last heel and shoe upper. 85

42. A last pulling machine having, in combination, gripping means movable to engage and hold a shoe, means to hold a last, mechanism operable to move and hold said gripping means in a position to engage and hold a shoe and subsequently operable to effect relative movement between said shoe and last in a direction to effect separation of said shoe and last, a movable frame 90 arranged to inclose a part, at least, of the shoe upper, upper turning means carried by said frame, means coöperating with said mechanism and operable, when said shoe is gripped and held, to move said frame and turning means into operative relation to the shoe upper, with means controlled by said mechanism and subsequently operable to actuate said turning means to turn the top of said 95

upper back toward the heel to afford clearance between the last heel and shoe upper. 100

43. Shoe handling mechanism comprising, in combination, means for supporting a last having a shoe thereon, upper gripping means movable to engage and grip the top 105

of the shoe upper and subsequently movable to fold the gripped upper back toward the heel.

44. Shoe handling mechanism comprising, in combination, means for supporting a last having a shoe thereon, upper gripping means movable in a direction to engage and grip the top of the upper at opposite sides of and adjacent to the back stay and subsequently movable in a different direction to fold the gripped upper back toward the shoe heel.

45. Shoe handling mechanism comprising, in combination, means for supporting a last having a shoe thereon, a movable frame arranged to inclose a portion, at least, of the upper, upper gripping means on the frame, means to move the frame to operatively position the gripping means relative to the upper, and means to operate the gripping means to turn the top of the upper back toward the heel.

46. Shoe handling mechanism comprising, in combination, means for supporting a last having a shoe thereon, a movable frame arranged to inclose, in part at least, the rear portion of the upper, oppositely disposed gripping means carried on said frame, means to move the frame to position the gripping means to grip the top of the upper at opposite sides of and adjacent to the back stay and subsequently movable in a different direction to fold the gripped upper back toward the shoe heel.

47. A last pulling machine having, in combination, means for holding a shoe, means for holding a last, means for effecting movement of said last holding means to remove the last from the shoe, and means operative during such movement to stretch the shoe counter to facilitate removal of the last.

48. A last pulling machine having, in combination, means for holding a shoe, means for holding a last, means for effecting movement of the last holding means to remove the last from the shoe, and means, operative during such movement and before the last heel has cleared the counter, to stretch the shoe counter to facilitate removal of the last.

49. A last pulling machine having, in combination, means for holding a shoe, means for holding a last, means for effecting movement of said last holding means to move the last in a direction substantially perpendicular to the plane of the shoe bottom and then in a direction generally lengthwise of the shoe to remove the last from the shoe, and means operative during such movement and before the last heel has cleared the shoe counter to stretch the counter to facilitate removal of the last.

50. A last pulling machine having, in combination, means for holding a shoe,

means for holding a last, means for effecting movement of the last holding means to remove the last from the shoe, and means operative during such movement to stretch the shoe upper above the counter back- 70 wardly toward the heel, in turn to stretch the counter so as to facilitate removal of the last.

51. A last pulling machine having, in combination, means for holding a shoe, 75 means for holding a last, mechanism for effecting movement of said last holding means completely to remove the last from the shoe, and means controlled and operated by said mechanism during such movement to spread the upper portion of the shoe counter, to facilitate removal of the last.

52. A last pulling machine having, in combination, means for holding a shoe, 80 means for holding a last, mechanism for effecting movement of said last holding means completely to remove the last from the shoe, and means, controlled and operated by said mechanism during such movement and prior to the time the last heel clears the 85 shoe counter, to spread the shoe counter to facilitate removal of the last.

53. A last pulling machine having, in combination, means for holding a shoe, 90 means for holding a last, means for effecting movement of said last holding means to remove the last from the shoe, and means operative during such movement to turn back and stretch the shoe upper above the counter in turn to spread the counter so as 100 to facilitate removal of the last.

54. A last pulling machine having, in combination, means for holding a shoe, 105 means for holding a last, mechanism for effecting relative movement of said shoe and last in a direction to separate said shoe and last, and means controlled by said mechanism and operated during separating movement and prior to the time the last heel clears the shoe counter, to grip and turn 110 back the shoe upper above the counter with outward tension to spread the counter so as to facilitate movement of the last heel out of the counter portion of the shoe.

55. A last pulling machine having, in combination, means for holding a last, 115 means for holding a shoe including hinged members arranged to embrace at least in part the rear of the upper and to engage said rear part at opposite sides of the longitudinal axis of the shoe and means to engage the opposite sides of the shank portion of the shoe, and mechanism for effecting relative movement of said last holding and shoe holding means in a direction to 120 separate a shoe and last.

56. A last pulling machine having, in combination, means for holding a last, means for holding a shoe including means to engage opposite sides of the shank por- 125 130

tion of the shoe and hinged members to engage the rear part of the upper at opposite sides of the longitudinal axis of the shoe, and mechanism for effecting relative movement between said last holding and shoe holding means in a direction to separate a last and shoe.

57. A last pulling machine having, in combination, means for holding a last,

10 means for holding a shoe including hinged members arranged to yieldingly embrace at least in part the rear of the upper and to engage said rear part at opposite sides of the longitudinal axis of the shoe and means 15 to engage the opposite sides of the shank portion of the shoe, and mechanism for effecting relative movement of said last holding and shoe holding means in a direction to separate a shoe and last.

20 58. A last pulling machine having, in combination, means for holding a last, means for holding a shoe including means arranged to yieldingly engage the rear part 25 of the upper at opposite sides of the longitudinal axis of the shoe, said engaging means being formed and arranged also to conform substantially to the vertical contour of the counter at the extreme rear end of the shoe to resist movement of the heel

30 end of the shoe in a plane perpendicular to the plane of the shoe bottom, and mechanism for effecting relative movement of said last holding and shoe holding means in a direction to separate a shoe and last.

35 59. A last pulling machine having, in combination, means for holding a last, means for holding a shoe including means to engage opposite sides of the shank portion of the shoe and hinged members to 40 yieldingly engage the rear part of the upper at opposite sides of the longitudinal axis of the shoe, and mechanisms for effecting relative movement between said last holding and shoe holding means in a direction to separate a last and shoe.

45 60. A last pulling machine having, in combination, means for holding a last, means for holding a shoe including means yieldingly to engage opposite sides of the shank portion of the shoe and hinged members arranged to embrace at least in part the rear portion of the upper and to yieldingly engage the rear part of the upper at opposite sides of the longitudinal axis of 55 the shoe, and mechanism for effecting relative movement between said last holding and shoe holding means in a direction to separate a last and shoe.

60 61. A last pulling machine having, in combination, means for holding a last, means for holding a shoe including hinged members arranged to embrace at least in part the rear portion of the upper and to engage yieldingly the rear part of the upper 65 at opposite sides of the longitudinal axis of

the shoe, said engaging means being formed and arranged to conform substantially to the vertical contour of the counter at the back of the shoe to resist movement of the heel end of the shoe in a plane perpendicular to the plane of the shoe bottom, and mechanism for effecting relative movement of said last holding and shoe holding means in a direction to separate a shoe and last.

62. A last pulling machine having, in combination, last holding means, shoe holding means including means to engage the back of the shoe upper to facilitate positioning a shoe in operative relation and mechanism for effecting movement of said last holder to remove a last from a shoe, including movement of the last substantially perpendicular to the plane of the shoe bottom, said back engaging means being formed and arranged to conform substantially to the vertical contour of the counter at the extreme rear end of the shoe to resist movement of the heel end of the shoe in a direction substantially perpendicular to the plane of the shoe bottom.

63. A last pulling machine having, in combination, means for normally holding a shoe tipped about its transverse axis, means for holding a last, and mechanism for effecting relative movement between said shoe and last in a direction substantially perpendicular to the plane of the shoe bottom and then in a direction generally lengthwise of the shoe and last to effect separation of the shoe and last.

64. A last pulling machine, having in combination, means for normally and adjustably holding a shoe tipped about its transverse axis, means for holding a last, and mechanism for effecting relative movement between said shoe and last in a direction substantially perpendicular to the plane of the shoe bottom and then in a direction generally lengthwise of the shoe and last to effect separation of the shoe and last.

65. A last pulling machine having, in combination, means for normally holding a shoe tipped about its transverse axis, means for holding a last, and mechanism for effecting relative movement between said shoe and last in a direction substantially perpendicular to the plane of the shoe bottom and then in a direction generally lengthwise of the shoe and last to effect separation of the shoe and last, said shoe holding means being constructed and arranged to prevent movement of the shoe in the direction of separating force and to permit movement of the shoe fore-part in the opposite direction during shoe and last separating movement.

66. A last pulling machine having, in combination, means for holding a shoe by its counter and shank portions, means for holding a last, mechanism for effecting relative

movement between said shoe and last in a direction substantially perpendicular to the plane of the shoe bottom and then in a direction generally lengthwise of the shoe 5 and last to effect separation of the shoe and last, said shoe holding means permitting movement of the shoe forepart in a direction substantially perpendicular to the plane of the shoe bottom and opposed to the direction 10 of separating force during such shoe and last separating movement.

67. A last pulling machine having, in combination, means for normally and adjustably holding a shoe tipped about its transverse axis, means for holding a last, and mechanism for effecting relative movement between said shoe and last in a direction substantially perpendicular to the plane of the shoe bottom and then in a direction generally lengthwise of the shoe and last to effect separation of the shoe and last, said shoe holding means being constructed and arranged to prevent movement of the shoe in the direction of separating force and to 20 permit movement of the shoe forepart in the opposite direction during shoe and last separating movement.

68. A last pulling machine having, in combination, means for holding a shoe including a heel height gage to properly position the shoe, means for positioning said holding means and gage to normally hold a shoe tipped about its transverse axis, means for holding a last, and mechanism for effecting relative movement between said shoe holding means and said last holding means in a direction substantially perpendicular to the plane of the shoe bottom and then in a direction generally lengthwise of the shoe and 30 last to separate the shoe and last.

69. A last pulling machine having, in combination, means for holding a shoe including a heel height gage to properly position the shoe, means for adjustably positioning the shoe, means for adjusting said holding means and gage to hold a shoe tipped about its transverse axis, means for holding a last, and mechanism for effecting relative movement between said shoe holding means and said last holding means 45 in a direction substantially perpendicular to the plane of the shoe bottom and then in a direction generally lengthwise of the shoe and last to separate the shoe and last.

70. A last pulling machine having, in combination, means for holding a shoe including a heel height gage to properly position the shoe, means for positioning said holding means and gage to normally hold a shoe tipped about its transverse axis, means for holding a last, and mechanism for effecting relative movement between said shoe holding means and said last holding means in a direction substantially perpendicular to the plane of the shoe bottom and 55 then in a direction generally lengthwise of

the shoe and last to separate the shoe and last, said shoe holding means being constructed and arranged to prevent movement of the shoe in the direction of separating force and to permit movement of the shoe 70 forepart in the opposite direction during shoe and last separating movement.

71. A last pulling machine having, in combination, last holding means, shoe holding means including means for engaging the shank portion of the upper at opposite sides and constructed to oppose heel-ward movement of the shoe, and mechanism for effecting relative movement between said last and shoe holding means in a direction to separate the shoe and last.

72. A last pulling machine having, in combination, last holding means, shoe holding means including means for engaging the shank portion of the upper at opposite sides, 85 said means having their contact faces shaped to conform to the longitudinal contour of the shank portion of the upper so as to oppose heel-ward movement of the shoe, and mechanism for effecting relative movement 90 between said last and shoe holding means in a direction to separate the shoe and last.

73. A last pulling machine having, in combination, last holding means, shoe holding means including means for engaging the shank portion of the upper at opposite sides having contact faces shaped to conform to the longitudinal and vertical contour of the shank portion of the upper to prevent heel-ward movement and movement in a plane 100 at an angle to the plane of the shoe bottom, and mechanism for effecting relative movement between said last and shoe holding means in a direction substantially perpendicular to the plane of the shoe bottom and 105 then in a direction generally lengthwise of the shoe and last to separate the shoe and last.

74. A last pulling machine having, in combination, last holding means, shoe holding 110 means including means for engaging the shank portion of the upper at opposite sides, said means having contact faces shaped to conform to the longitudinal contour of the shank portion of the upper so as to oppose 115 heel-ward movement of the shoe, said contact faces being of compressible gripping material, and mechanism for effecting relative movement between said last and shoe holding means in a direction to separate 120 said last and shoe.

75. A last pulling machine having, in combination, last holding means, shoe holding means including means constructed to engage opposite sides of the shoe above the 125 plane of the sole at the shank of the shoe and arranged yieldingly to oppose movement of the shoe in a direction substantially perpendicular to the plane of the shoe bottom, and mechanism for effecting relative move- 130

ment between said last holding means and said shoe holding means in a direction to separate a shoe and its last.

76. A last pulling machine having, in combination, last holding means, shoe holding means including compressible gripping material for engaging the shank portions of the upper at opposite sides of the shoe, and mechanism for effecting relative movement between said last and shoe holding means in a direction to separate said last and shoe.

77. A last pulling machine having, in combination, means to engage and hold a shoe for the removal of its last, last engaging and holding means including a last pin mounted for turning movement to accommodate itself to variations in the angular position of lasts, and mechanism for moving the last pin to pull the last in a direction substantially perpendicular to the plane of the shoe bottom and then in a direction generally lengthwise heelward of the shoe to remove the last from the shoe.

78. A last pulling machine having, in combination, means to engage and hold a shoe for the removal of its last, last engaging and holding means including a pulling member, a carrier pivotally connected at one end to said member and having a last pin thereon free to rotate about its longitudinal axis, and mechanism for actuating said pulling member to move said carrier and last pin to pull the last in a direction substantially perpendicular to the plane of the shoe bottom and then in a direction generally lengthwise heelward of the shoe to remove the last from the shoe.

79. A last pulling machine having, in combination, means for holding a shoe, means for holding a last, means for effecting relative movement between said shoe and last in a direction to separate said shoe and last, and means for laterally stretching said shoe to facilitate separation of said shoe and last.

80. A last pulling machine having, in combination, means for holding a shoe, means for holding a last, means for effecting movement of said last holding means to remove the last from the shoe, and means operative during such movement laterally to spread the counter portion of the shoe.

81. A last pulling machine having, in combination, means for holding a shoe, means for holding a last, means for effecting relative movement between said shoe and last in a direction to separate said shoe and last, and means operative during such separating movement and before the last heel has cleared the shoe counter to stretch the shoe counter transversely of the shoe and last to facilitate the separation of the shoe and last.

82. A last pulling machine having, in combination, means for holding a shoe, means for holding a last, means for effecting relative

movement between said shoe and last in a direction to effect separation of said shoe and last, and means for engaging the top of the upper at its rear end to pull the upper backwardly and toward the sole at the heel to facilitate such relative separating movement.

83. A last pulling machine having, in combination, means for holding a shoe, means for holding a last, mechanism for effecting relative movement between the shoe and last in a direction to effect separation of the shoe and last, and means automatically engaging the top of the upper above the counter adjacent to the back stay to pull the upper backwardly and toward the sole at the heel of the shoe to facilitate such relative separating movement of the shoe and last.

84. A last pulling machine having, in combination, means for holding a shoe, means for holding a last, means for effecting relative movement between said shoe and last in a direction substantially perpendicular to the plane of the shoe bottom and then in a direction lengthwise heelward of the shoe and last to effect separation of the shoe and last, and a member arranged to engage the top of the upper above the counter adjacent to the back stay, with mechanism for automatically moving said member to pull the rear portion of the shoe upper rearwardly and toward the sole at the heel of the shoe to afford clearance between the shoe and last heel during such separating movement.

85. A last pulling machine having, in combination, means for holding a shoe for the separation of a last from the shoe, means for holding the last, means for pulling the last from the shoe in a direction substantially perpendicular to the plane of the shoe bottom and then in a direction generally lengthwise heelward of the shoe, and means to engage the top of the shoe upper above the counter to pull the rear portion of the upper rearwardly and toward the sole at the heel to afford clearance between the shoe upper and the heel of the last during such separating movement.

86. In a last pulling machine having last holding means and shoe engaging means relatively movable to effect the separation of a shoe and its last, a member for engaging the tread face of a shoe heel to position the shoe relatively to said shoe holding means, said member being mounted for angular adjustment of its heel engaging face about an axis extending transversely of the heel of an engaged shoe.

87. In a last pulling machine having last holding means and shoe gripping means relatively movable to effect the separation of a shoe and its last, a heel height gage positioned adjacent to the shoe gripping means for engaging the tread face of a shoe heel

and mounted for tilting adjustment about an axis extending transversely of a gripped shoe.

88. In a machine for effecting the complete separation of a shoe and its last, last holding means and shoe holding means arranged for relative movement completely to separate a shoe and its last, and means operable to pull backwardly the rear end of the top of a high shoe to provide clearance between the last heel and the inside back stay portion of the shoe top.

89. In a machine for effecting automatically the complete separation of a shoe and its last, last holding means, shoe holding means, power operated mechanism for effecting relative movement of said means completely to separate a shoe and its last, and mechanism constructed and arranged automatically to pull backwardly heelward of the shoe the back stay portion of the top of a high shoe to afford clearance for the heel of its last in the separation of the last and shoe.

90. In a machine for effecting the complete separation of a shoe and its last, last holding means and shoe gripping means arranged for relative movement completely to separate a shoe and its last, and mechanism automatically operative, prior to movement of the last heel lengthwise beyond the shoe counter, to pull lengthwise rearwardly the back stay portion of the top of a high shoe to provide clearance for the heel of the last.

91. In a machine for effecting the complete separation of a last from its shoe, shoe gripping means, last holding means, power operated mechanism for moving the last holding means completely to pull the last

from a gripped shoe, and mechanism operative automatically in timed relation to the separation of the last to pull lengthwise rearwardly the back stay portion of the top of a high shoe to afford clearance for the last

45 heel.

92. In a last pulling machine, the combination of a last support, means operable to engage the shoe on a last mounted on said support, mechanism for operating said means to loosen the shoe on its last to facilitate the separation of the shoe and last and mechanism for effecting relative movement of said support and the shoe engaging means having a component in a direction lengthwise of the shoe and last to separate the shoe and last.

93. In a last pulling machine, the combination of shoe engaging means and a last support relatively movable to position the shoe on a supported last and said engaging means in coöperative relation, mechanism for operating said means to engage and loosen the shoe on its last to facilitate the separation of the shoe and last, and mechanism for effecting relative movement of the

last support and shoe engaging means, said movement having a component in a direction lengthwise of the shoe and last, to separate the shoe and its last.

94. In a last pulling machine, the combination of a last support, means operable to engage the shoe on a last mounted on said support, a main drive shaft, connections from said drive shaft organized to operate said engaging means to loosen the shoe on its last to facilitate separation of the shoe and last and a separate train of mechanism operated by said drive shaft and including a cam mounted on said drive shaft relatively to move said last support and shoe engaging means in a direction to separate the last and its loosened shoe.

95. In a last pulling machine, the combination of a last support, shoe engaging means, mechanism for operating said means to engage and loosen the shoe on a last mounted on said support to facilitate removal of the last, and mechanism for moving said support with its last relatively to said engaging means, said movement having a component lengthwise of the last and shoe, to withdraw the last from the shoe.

96. In a last pulling machine, the combination of means for engaging a shoe, a last support movable to present the shoe on a supported last in coöperative relation to said shoe engaging means, and mechanism constructed and arranged for operation to actuate said means to engage and loosen a presented shoe on its last to facilitate the withdrawal of the last and to move the last support and last relatively to the shoe engaging means to withdraw the last from the shoe.

97. A last pulling machine, having in combination, a last support, means movable to grip the shoe on a supported last, and mechanism organized to operate said means to grip and loosen the shoe on its last to facilitate removal of the last and to move said last support with the last relatively to said gripping means to withdraw the last from the loosened shoe.

98. In a machine for separating a shoe and a last the combination of a last support movable longitudinally of a supported last and shoe, shoe engaging means movable in a substantially vertical direction relatively to said last support into position to engage the shoe on a last mounted on said support, mechanism for operating the positioned shoe engaging means to loosen the shoe, and mechanism for moving said last support and last lengthwise of the shoe and relatively to said engaging means to remove the last from the shoe.

99. A machine for separating a shoe and last having means for moving the forepart of the upper of the shoe relatively to the forepart of the last to better the longitudinal separation of the shoe and the last, and

shoe and last separating means positioned at the heel of the last.

100. In a last pulling machine, the combination of a last support, means operable to grip the upper of the shoe on a last mounted on said support, and mechanism for relatively moving said support and shoe grip-

ping means to separate the shoe and last and for operating said means to loosen the shoe on its last to facilitate the separation of the 10 the shoe and last.

In testimony whereof I have signed my name to this specification.

MICHAEL F. BROGAN.
